COMBINED ERASING, BLOTTING, AND ERASER CLEANING IMPLEMENT

Clarence Earl Thompson, Los Angeles, Calif.

Application November 30, 1950, Serial No. 198,328

4 Claims. (Cl. 120—36)

1

My invention relates to a combined erasing, blotting and eraser cleaning implement in which the combinative whole contributes to the unitary result of making an erasure in a quicker, simpler, cheaper and neater manner.

Take for example the typist. When a typographical error is made it must be corrected. Certain problems present themselves when this operation is to be performed. It should be done as quickly as possible which is understandable. It should be done meticulously, in order not to disclose the awareness of the mistake. It should be painstakingly performed so as not to mar or puncture onion skin carbon copies which are not only delicate in texture but also very easy to smudge. In order to expedite the operation there is needed first the blotter to remove excess carbon and/or ink, a clean eraser to perform the erasing operation and means to clean the eraser incident to a repeat erasing operation.

In so far as I have been able to ascertain by careful research no implement has as yet been improvised which gives to the typist or the writer and draftsman an article which through its use secures the plural advantages of obviating the numerous disadvantages occurring through the employment of present day erasing, cleaning and blotting devices.

Accordingly, important objects of the invention are:

To provide a novel and improved combination of eraser, eraser cleaner and blotter; a new and more efficient means for cleaning the eraser after the same becomes soiled; and a new and improved mode of assembling the eraser in relation to the eraser;

To provide a typist's accessory which is easier to manufacture, that is to say, provide a device having a minimum of separate parts and involving less cost in their assembly;

To provide an inexpensive article which may be retailed within a few cents of conventional erasers now provided, one having greater longevity due to the fact that it need not be discarded after partial use on account of being out of shape or ingrained with dirt;

To provide an article of the above stated kind capable of greater variety of uses and an article wherein the pressure of the eraser cleaner unit may be regulated to cover greater or less areas to be cleaned, as desired, and wherein the cleaning elements (i. e. bristles) are always maintained alive throughout their period of use in order further not to contaminate a slightly discolored eraser; and

To provide a one piece sheet metal combined

2

mounting and handle means which in its completed form has a wall with interlocking edge portions that stabilize it against being strained out of shape during use.

5 Still other objects, advantages and features of the invention will hereinafter appear.

Referring to the accompanying drawing wherein is shown an embodiment of the invention now deemed preferable.

10 Fig. 1 is a side elevation of a combined eraser, eraser cleaner and blotter, embodying my new device, parts being broken away to disclose underlying structure.

Fig. 2 is an exploded view of the several parts, 15 shown in perspective.

Fig. 3 is an enlarged, longitudinal midsection of the eraser cleaner per se.

Fig. 4 is an expanded view of the blank for 20 the body portion of the device.

Fig. 5 is a perspective view of the body portion of the device ready for use, one wing thereof being turned back to illustrate the joint seam.

25 Fig. 6 is a perspective view of the blotting member per se, a portion of the spirally wrapped paper strip being turned back to further disclose said blotting member.

Fig. 7 is a cross section on line 7—7 of Fig. 1.

Referring in detail to the drawing therein is shown, in assembly in Fig. 1, the principal parts comprising the invention, namely, the conventional circular eraser 8, the body 9, on which said eraser is rotatably mounted and in which is adjustably housed the eraser cleaner 10 and blotting member 11.

The body 9 forms a mounting member and 35 handle and is constructed from a flat, sheet metal part 12, the blanked out piece being shown in Fig. 4. In Fig. 5 said blanked out piece is partially formed into its true shape, the completely, rectangularly formed part being shown in Fig. 2.

40 In the blank construction shown in Fig. 4, it will be seen that the blank is constructed so as to provide ears 13 and 14, said ears, in the modeled or shaped-up form being adapted to provide a bifurcation between the branches of 45 which the eraser 8 is rotatably held on a tubular rivet pin 15, a washer 16 being provided to overlie each side of the eraser against which the inside face of an ear abuts.

In the completed article a longitudinal slot 20 (see Figs. 2 and 4) is provided through one side wall of the aforesaid holder 9, and being adapted to form a guide for a manually graspable curl 25 carried by the sheet metal sheath 26 which grips the handle of bristles 27 of the aforesaid cleaner

55 10. Sheath 26 is surrounded transversely by an

indented groove 28 whose convexity causes the bundle of bristles to be held securely in place. Said sheath is put into place by advancing it between the ears 13, 14 in a tilted manner until said curl 25 passes under the bridge 29, whereupon said sheath may be brought to the slidable position shown in Fig. 1. Said bristle bundle is shown having its cleaning or applicator end portion (see Fig. 2) as arcuate at 27a in a vertical manner and at 27b in a horizontal manner, to correspond, respectively to circumferential and transverse curvatures of the eraser 8. The horizontally arcuate feature increases the width of eraser surface cleaned by the bristles.

Returning to the aforesaid blotting member 11, this member is desirably made of a plastic clay with a rubber base which is a kneadable clay adapted to absorb typing carbon, thus facilitating the erasing operation and leaving a less smutty appearance. Also it absorbs excess surface ink to expedite erasing. It is rectangular in cross section and has spirally wrapped around it a paper strip 30. This wrapped blotting member is shown having its inner end portion gripped by a sheet metal clip 31 of a rectangular U shape. This clip is slidably contained within the holder member 9 and is provided near its open end with an outwardly directed curl 32 which projects outwardly through and slidably fits within a longitudinal slot 33, the outer end of said slot forming a stop which prevents separation of said clip from the holder 9. Said slot 33 has a series of enlargements resulting from oppositely disposed arcuate notches 33a.

From Fig. 7 it will be seen that the curl 32 has a contracted neck portion 34 which is narrow enough to glide freely along all portions of the slot 33 the outer end portion of said curl being too large to pass through said slot except where the latter is widened by the aforesaid arcuate notches 33a.

Preparatory to putting the blotting member 11 and clip 31 into place, one end of said blotting member is wedged in between the arms of said clip (the latter being resilient), and then the clip is inserted into the end of the member 9 with the ear 32 directed toward the slotted side of said member, until said ear abuts the end of said member. Thereupon the ear carrying flange of the clip is sprung inwardly until the ear can be moved into the member 9, this being done thus bringing said ear into alignment with the outer part of the slot 33 and allowing it to spring out through the widened outer end portion of said slot, it being understood that the elastic material of which the blotting member is composed is sufficiently compressible to allow this to be done.

By preference as shown the blank 12 is provided along one long edge with a plurality of triangular projections 35 and along its opposite edge with corresponding triangular recesses 36. When said blank has been shaped up so as to form the body 9 said points are nested into said recesses thus interlocking the edge portions of the blank, so that a stable handle forming structure results, even though no fastening means is used to secure said edge portions to each other.

In operating the device upon typed matter the typist will use the holder or body 9 as a handle means with which first to apply to typing to be erased the blotting member 11 and thereafter the eraser 8 to erase from the page being typed the typing on the area to which said blotting member has been applied. In applying said blotting member the typist will press a finger or

thumb toward the right (viewing Fig. 1) against the curl 32 when that is necessary to cause the outer end of a worn down bar 11 to project from the member 9. Depressing the thicker outer end portion of the curl into the selected widened portion of the slot will enable the operator more conveniently to prevent the retraction of the blotting member while in use.

Whenever, by reason of use, the eraser 8 becomes soiled, the typist, in order to clean it, will rotate it with one hand while using the other hand gently to press the bristle bundle 27 against its periphery, the latter operation being performed by pressing the thumb or finger against the back side of the curl 25.

In using the eraser cleaning bundle of bristles the operator will apply the bristle ends to the eraser 8 with more or less pressure depending upon the substance and amount of discoloring material to be removed by rotating said eraser over the applied bristles, thus cleaning it with a brushing or sweeping action, the bristles being bendable enough to create more effective cleaning area and to provide the brushing or sweeping action desired.

I claim:

1. In an eraser, an elongated handle forming member, a circular eraser element rotatably mounted on one end of said handle member, a tubular holder fitted to slide longitudinally in a tubular slotted end part of said handle member, a projection fixed on said holder projecting through the slot in said handle member, and a multiplicity of brush forming bristles fixed in said holder with ends of the bristles projecting from an end of the holder toward the eraser so that the ends of the bristles are adapted to be pressed against the periphery of the eraser by manual movement of the projection on the holder.

2. An eraser as claimed in claim 1 wherein the eraser contacting ends of said bristles form a concavity conforming to the circumferential and transverse curvature of the periphery of the eraser element.

3. An eraser as claimed in claim 1 wherein said bristle holder is formed with an indented groove to tightly compress the bristles in the holder.

4. An eraser as claimed in claim 2 wherein said handle member is formed from a unitary sheet bent to provide a tubular handle and having a pair of complementary integral ears extending longitudinally from one end of the tubular handle, and a disk shaped eraser rotatably mounted between said ears with the bristles slidably radially of the eraser and completely contacting the edge and adjacent marginal portion of the eraser.

CLARENCE EARL THOMPSON.
